(57) **CLAIM**

We claim the ornamental design for a siren lamp automobile air freshener, as described and shown in FIGS. 1 and 2.

DESCRIPTION

FIG. 1 is a front view of an air freshener embodying aspects of the present invention; and,

FIG. 2 is a top view of the air freshener shown in FIG. 1. The broken line showing of the environment is for illustrative purposes only and forms no part of the claimed design.
